UNITED STATES PATENT OFFICE.

RAYMOND E. CRANE, OF CAMERON, WEST VIRGINIA.

DESIGN FOR A WATER-CLOSET-CISTERN CASING.

No. 39,322.

Specification for Design.

Patented May 26, 1908.

Application filed February 18, 1908. Serial No. 416,583. Term of patent 14 years.

To all whom it may concern:

Be it known that I, RAYMOND E. CRANE, a citizen of the United States, residing at Cameron, in the county of Marshall and State of West Virginia, have invented a new, original, and ornamental Design for a Water-Closet-Cistern Casing, of which the following is a specification, reference being had to the accompanying drawing, forming part thereof.

The figure is a front view of the cistern, showing my new design.

I claim:
The ornamental design for a water closet cistern casing, as shown.
